UNITED STATES PATENT OFFICE.

WILLIAM O. NICELEY, OF NEW YORK, N. Y., ASSIGNOR TO THE E. G. LANG MANUFACTURING COMPANY, OF NEW YORK, N. Y., A CORPORATION OF NEW YORK.

MERCHANDISE-DISPLAY CONTAINER.

Application filed September 17, 1921. Serial No. 501,403.

To all whom it may concern:

Be it known that I, WILLIAM O. NICELEY, a citizen of the United States, residing at 606 West 116th Street, in the borough of Manhattan, in the county of New York, city and State of New York, have invented certain new and useful Improvements in a Merchandise-Display Container, of which the following is a specification.

10 This invention relates to a display container for merchandise, and the novelty consists in the adaptation and arrangement of the parts, as will be more fully hereinafter pointed out.

15 A large number of sets of tabs of different sizes and types must be carried by merchants handling tabs. It is also essential that these should be displayed in such a way that the different types of tabs and different sizes 20 may be easily and quickly picked out by the customer as well as by the salesman.

25 My invention solves this problem by furnishing a container having separate partitioning cells which may be of any desired size and adapted to hold tabs or other merchandise and having combined therewith a cover embodying in its open position specimens of said tabs or merchandise, and means for indicating the location of said tabs or 30 merchandise in said container so that they may be quickly and easily found by either the customer or the salesman.

35 Referring to the drawings, Figure 1 is a perspective of my container; and Figure 2 is a detail of one of the independent partitioning cells.

In the drawings 3 is a container on which is mounted a cover 4 by means of a flexible hinge 5.

40 Flexible retaining members 6 are rigidly secured to the box 3 at 7 and to the cover 4 at 8, so that the cover 4 can be raised to an open position slightly more than 90° relative to the box 3, and will be retained in such 45 position by means of the flexible retaining members 6.

Independent partitioning cells 9 which are made in the form of topless and bottomless boxes are placed in the container 3 so that 50 the inside space of the container is filled thereby, but the said cells 9 may be made in whatever size and shape is required in accordance with the size and shape of the merchandise to be placed therein, as indicated

by the longitudinal cell 10 shown in the 55 front of the container 3.

Sets of tabs, such as the days of the week or months of the year, etc., are placed in envelopes 11 and then placed in the independent cells 9.

60 Specimens 12 of the tabs or merchandise contained in the envelopes 11 are mounted on the inside of the cover 4, and the identification marks 13 also are placed on the inside of the cover 4 opposite the specimens 12. 65

For convenience in arrangement the tabs or merchandise indicated by specimens 12 are placed in envelopes in the independent cells 9 in the row under which the said merchandise is indicated by the similar specimen 70 in the column of specimens above it. This arrangement is further simplified by using the cell 9 at the rear of the container 3 under the first specimen column for holding the tabs or merchandise indicated by the lower 75 specimen 12 of the first column and using the next to the back cell 9 for containing the merchandise represented by the second specimen from the bottom of the first column of specimens 12. This particular arrangement 80 is not essential, but this or a similar one is essential to the orderly arrangement of the merchandise so that it can be readily found under the column in which the specimen is found and in the same relative position in 85 the container, as indicated by the relative position of the specimen in the column.

Many variations can be made in the arrangement of the parts without departing from the spirit of the invention, and I do 90 not confine myself to the precise arrangement shown.

I claim:

1. In a merchandise display container the combination of a large box, a group of bottomless boxes therein, envelopes in said bottomless boxes each adapted to hold a set of index tabs, a cover to said large box having a flexible hinge, flexible retaining members adapted to limit the opening of said cover 95 and support it in such opened position, and specimens of said tabs mounted on the inside of said cover so as to indicate the location of the same in said large box. 100

2. In a merchandise display container the combination of a large box, a group of independent partitioning cells therein, envelopes in said cells each adapted to hold a set of 105

merchandise, a cover to said large box having a flexible hinge secured on one edge to said box, and a pair of flexible retaining members adapted to support said cover in the opened position.

3. In a merchandise display container the combination of a large box, a group of independent partitioning cells therein, envelopes in said cells each adapted to hold a set of merchandise, a cover to said large box having a flexible hinge secured on one edge to the box, a pair of flexible retaining members adapted to support said cover in the opened position, and specimens of said merchandise displayed on the inside of said cover.

4. In a merchandise display container the combination of a large box, a group of independent partitioning cells therein, envelopes in said cells each adapted to hold a set of

merchandise, a cover to said large box having a flexible hinge secured on one edge to the box, a pair of flexible retaining members adapted to support said cover in the opened position, specimens of said merchandise displayed on the inside of said cover, and means for locating such merchandise in said box.

5. The combination in a merchandise display container of a large box, a group of smaller boxes therein, envelopes in said smaller boxes each containing merchandise, a cover to said large box having a hinge, retaining means for holding said cover in the open position, and means for indicating the kind and location of said merchandise in said large box when said cover is in the open position.

In testimony whereof I affix my signature.

WILLIAM O. NICELEY.
